HAND PUMP

Eugene L. Kilbourn, Marengo Township, Calhoun County, and Doyle M. Fellers, Marshall Township, Calhoun County, Mich., assignors to S. H. Leggitt Company, Marshall, Mich., a corporation of Michigan

Filed May 11, 1962, Ser. No. 70,083

Term of patent 14 years

(Cl. D65—1)

FIGURE 5 is a top plan view thereof with the dispensing spout and handle rotated 90 and 45 degrees respectively.

The dominant features of our design reside in the portions shown in full lines with the broken line portions omitted in FIGURES 2 through 5 for convenience of illustration.

We claim:

The ornamental design for a hand pump, as shown and described.
